UNITED STATES PATENT OFFICE.

WILLARD J. GOODFELLOW, OF BENTLEY SPRINGS, MARYLAND.

MACHINE FOR MAKING CIGAR-WRAPPERS FROM TOBACCO-STEMS.

1,332,252.

Specification of Letters Patent.

Patented Mar. 2, 1920.

Application filed April 11, 1919. Serial No. 289,260.

To all whom it may concern:

Be it known that I, WILLARD J. GOODFELLOW, a citizen of the United States, residing at Bentley Springs, in the county of Baltimore and State of Maryland, have invented 5 certain new and useful Improvements in Machines for Making Cigar-Wrappers from Tobacco-Stems; and I do hereby declare the following to be a full, clear, and exact description of the invention, such as will enable others skilled in the art to which it 10 pertains to make and use the same.

This invention has reference to the conversion of tobacco stems into cigar wrappers, and one of its objects is the provision 15 of a machine by means of which tobacco stems may be converted into cigar wrappers having the appearance of those wrappers made from the natural tobacco leaf.

20 A further object of the invention is the provision of a machine of the above stated character by means of which tobacco stems may be formed into a continuous sheet or web in which the fibers are so arranged as 25 to prevent the tearing of the web lengthwise during its passage through the machine.

A further object of the invention is the provision of a machine of the above stated 30 character which may be set up and operated in an ordinary pulp and paper mill, which will be comparatively simple, durable and efficient, and which may be manufactured and sold at a comparatively low cost.

With the above and other objects in view, 35 the invention consists in the construction, combination and arrangement of parts hereinafter fully described and claimed, and illustrated in the accompanying drawings wherein:

40 Figure 1 is a sectional view taken on a plane extending centrally and vertically through the front part of the machine.

Fig. 2 is a similar view of the rear part of the machine,

45 Fig. 3 is a view in side elevation of the central part of the machine,

Fig. 4 is a view in side elevation of the rear end of the machine,

50 Fig. 5 is a sectional view taken on the horizontal plane indicated by the line 5—5 of Fig. 4, looking in the direction indicated by the arrow, the screen being omitted;

55 Fig. 6 is a detail view in side elevation of the apparatus by means of which tobacco liquor is fed to the liquor applying rolls of the machine,

Fig. 7 is a detail view and side elevation of one of the rolls for maintaining a film of uniform thickness of tobacco liquor upon the rolls used to apply the liquor to the web, 60 and

Fig. 8 is a detail plan view of one set of the rollers used to support the web during its passage between the liquor applying 65 drums.

Referring to the drawings by reference numerals, and particularly to Fig. 2, 1 designates a tank which has its upper side fully open. The tank is divided up into a large front compartment 2 and small rear compartments 3 and 4 by partitions 5 and 6. The partition 5, which has its upper end flush with the upper side of the tank 1, terminates short of the bottom of the tank to provide an opening 7 which establishes communication between the compartments 2 and 3. The partition 6, which has its lower end flush with the bottom of the tank 1, terminates short of the upper side of the tank to provide an opening 8 which establishes 75 communication between the upper ends of the compartments 3 and 4. A pulp vat 8^a is arranged within the compartment 2. The front wall 9 of the pulp vat 8^a is spaced from the front wall of the tank 1 and its upper 80 end terminates short of the upper end of the tank 1 to provide an opening 10 through which the pulp flows into the vat. The lower end of the front wall 9 of the pulp vat 8^a, and the bottom wall 11 thereof are 85 curved and spaced from the bottom wall of the tank 1. The rear wall 12 of the vat 8^a is spaced from the partition 5. The walls 9, 11 and 12 of the pulp vat, together with the front wall and bottom wall of the tank 95 1 and the partition 5, provide a substantially U-shaped compartment about the pulp vat 8^a. A making cylinder 12^a of any well known type is journaled within the pulp vat 8^a eccentrically with relation to the curved 100 bottom wall 11 of the vat. A couch roll 13 is journaled on pivoted arms 14. This roll is maintained in proper engagement with the making cylinder 12^a through the medium of weights 15 which are adjustably mounted 105 upon pivoted arms 16, these arms being connected to the arms 14 through the medium of adjustable links 17.

A first felt 18 passes about the guide rollers 19 and the couch roll 13. One of the 110 rollers 19 may be adjusted to maintain the felt 18 in proper tension through the me-

dium of a jack 20 of any well known construction. The top run of this felt passes over a suction box 22 and between the first set of press rollers 26 and 27. The bottom 5 run of this felt passes between sprays 23 and 24, is acted upon by a beater 25, and passes over a suction box 21.

A second felt 28 passes over the upper press roll 27, over guide rollers 29, and between a second set of press rolls 30 and 31. The upper press roll 31 is journaled in pivoted arms 32, and it is held in proper contact with the bottom press roll 30 by weights 33. The weights are adjustably mounted on 15 pivoted arms 34 which are connected to the arms 32 by adjustable links 35. A doctor 36, located in front of the upper press roll 31, is carried by the arms 32.

The bottom run of the second felt 28 20 passes under a suction box 37 and engages the first felt 18 directly beneath that suction box. This suction box is located in advance of the first set of press rolls 26 and 27, and it transfers the web from the first felt to 25 the second felt. A jack 29^a is connected to one of the guide rollers 29 and provides means by which the second felt may be kept in proper tension. Any suitable means, not shown, may be used for imparting motion 30 to the first and second sets of press rolls and the first and second felts.

To prepare the tobacco stems for conversion into sheet tobacco, they are first boiled in water in any vessel, not shown, suitable 35 for the purpose. The resultant liquor is drawn off, after which the stems are removed and converted into pulp in any well known manner. The pulp is fed by means, not shown, into the compartment 4. It flows 40 from this compartment through the opening 8 into the compartment 3, and it then flows through the opening 7 into the horizontal and vertical branches of the U-shaped compartment formed by the front, bottom and 45 rear walls of the pulp vat 8^a and the front wall and bottom wall of the tank 1 and the partition 5. The pulp then flows through the opening 10 into the pulp vat 8^a. The making cylinder 12^a and the couch roll 13 50 may be rotated in any well known manner, and the web formed upon the cylinder during its rotation is picked up by the first felt 18. This felt carries the web over the couch roll 13, over the suction box 22, and 55 between the first set of press rolls 26 and 27. At a point in advance of the first set of press rolls 26 and 27, the second felt 28 picks up the web and carries it under the suction box 37 and between the second set of press 60 rolls 30 and 31. The web 38 leaves the upper press roll 31, and is carried by an apron 39 through the front of the machine. In that portion of the machine the web is coated on both sides with tobacco liquor and 65 dried.

The pulp is, during its passage from the compartment 3 to the vat 8^a, agitated to set up therein forwardly flowing divergent currents. These currents cause the fibers to arrange themselves on the bias or angularly 70 with relation to the longitudinal center of the machine. It will thus be apparent that the fibers in the web will be angularly related to the longitudinal center thereof and that the fibers of the various groups of fiber 75 will be angularly related. In view thereof, the web is of such strength as to prevent its tearing longitudinally during its passage through the machine. The making cylinder is provided with a screen 12^b which is 80 so formed as to emboss the web in a manner that the wrappers made therefrom will have the appearance of those wrappers made from the natural tobacco leaf.

As will be apparent from Figs. 2 and 5, 85 the agitator comprises a shaft 40 and diametrically opposite blades or ribs 41. The blades or ribs are of angular formation with their apices directed outwardly so that they will form a diamond shaped figure in which 90 the shaft 40 is diagonally arranged. The agitator is rotated in the direction indicated by the arrow in Fig. 2 of the drawings very rapidly, and to permit of motion being imparted to the agitator the shaft 40 is pro- 95 vided with a belt wheel 42.

A trough 43 is located in the tank 1 in advance of the pulp vat 8^a to catch the pulp thrown out of the vat by the rotation of the making cylinder 12^a. By reference to Fig. 5 100 of the drawings, it will be seen that the intake pipe 44 of a rotary pump 45 is in communication with one end of the trough 43. The discharge of the pump 45 is in communication with the compartment 4 of the tank 1 through the medium of a pipe 46. All pulp accumulating in the trough 43 is returned to the tank 1, and as the pump is in continuous operation there will be no loss 105 of pulp due to the rotation of the making cylinder 12^a. To permit of its being operated, the pump 45 is equipped with a shaft 47 upon which is mounted a belt pulley 48.

By reference to Fig. 1 of the drawings, it 110 will be seen that the apron 39 passes about heating rolls 49, 50 and 51 and about guiding rollers 52. The heating rolls 49, 50 and 51 are of the usual construction and are rotated in the usual manner. One of the guiding rollers 52 is provided 115 with a jack 53 by means of which the apron 39 may be kept at proper tension. The web 38 passes about the heating roll 49 with the apron 39. After passing about the heating roll 49, the web 38 passes between 120 upper and lower coating rolls 54 and 55, respectively. These rolls are rotated in any suitable manner and are adapted to coat both sides of the web 38 with tobacco liquor. The web 38 is supported at each side 125 130

of the coating rolls 54 and 55 by angularly related rollers 56 and 57 which are shown in detail in Fig. 8 of the drawings. After passing over the rollers 56 and 57 located in advance of the coating rolls 54 and 55, the web 38 is carried by the apron 39 about the heating roll 51. The web 38 then passes over a spring supported roller 58 and thence about an adjustable reel 59. The reel is 10 slidably and rotatably mounted upon inclined supports 60 and it is rotated in a direction to wind the web thereon by the apron 39, it being held in contact with the apron by the web 38. To prevent the reel 59 from moving off of the support 60 when the machine is not in operation, stops 61 are provided.

The liquor used to coat both sides of the web 38 is produced by the boiling operation of the tobacco stems, and it is fed to a pan 62 located above the coating roll 55 by a pipe 63. The pipe is provided with a valve 64 by means of which the supply of tobacco liquor to the pan 62 may be regulated and controlled. A pipe 65, to which is connected a plurality of valved nozzles 66, communicates with the ends of the pan 62. The liquor is fed to the coating rolls 55 by the nozzles 66. A roller 67 is journaled adjacent the coating roll 55, and it is provided with a compound spiral rib 68 which contacts with the coating roll 55. The rib 68 extends in opposite directions from the transverse center of the roller 67, and it is 25 rotated in a direction reverse to the direction of rotation of the coating roll 55, its function being to prevent excess accumulation of liquor upon the coating roll 55. The excess liquor is carried to the ends of the roller 67 and flows into a pan 69 which is located below the coating roll 54. The coating roll 54 takes up the liquor from the pan 69 and applies it to the under side of the web and has associated therewith a roller 67^a 30 similar to the roller 67.

Having described my invention, what I claim is:

1. In an apparatus for the treatment of tobacco waste liquid and fiber containing means, liquid moving means operatively connected to said containing means, liquid baffling and propelling means in said containing means and at an angle to the movement of the liquid and of different widths, sheet forming and desiccating rollers, sheet-coating means and sheet supporting means at the sides of and above said sheet-coating means, and sheet drying means below said sheet-coating means.
2. In an apparatus for the treatment of tobacco waste in combination liquid and fiber-containing means, liquid moving means operatively connected to said containing means, liquid baffling and propelling means in said containing means and rotatable

therein and substantially at right angle to the movement of the liquid, sheet-forming and desiccating rollers, sheet-coating rollers and sheet-supporting means at the sides of and above said sheet-coating rollers, and sheet-drying rollers below said sheet-coating rollers.

3. In an apparatus for the treatment of tobacco waste in combination a partitioned overflow tank, a container, communicating with said overflow tank, a trough shaped container communicating with said overflow tank, and a sheet-forming roller eccentrically mounted in said trough, an overflow tank adjoining said trough, and liquid moving means operatively connected to both overflow tanks, rotatable liquid baffling and propelling means in the lower part of said container and presenting different widths in the direction of the movement of the liquid sheet-forming, supporting and propelling means outside of the tanks and the container and associated therewith, sheet-coating means, and sheet supporting means at the sides of and above said coating means, and sheet-drying rollers below said sheet-coating means.

4. In an apparatus for the treatment of tobacco waste and for the making of imitation tobacco, in combination a partitioned overflow tank, a container communicating with the bottom part of said overflow tank, a trough-shaped container communicating with said first container, and a sheet-forming roller eccentrically mounted in said trough, an overflow tank adjacent said trough, and liquid-moving means operatively connected to both overflow tanks, rotatable liquid-baffling and propelling means in the lower part of said container, and of laterally decreasing widths, sheet-forming, supporting and propelling means outside of the tanks and outside of the container, and associated therewith, sheet drying rollers, two sheet coating rollers, arranged in succession above said drying rollers, and sheet supporting and guiding means at the sides of said coating rollers, and above said drying rollers.

5. In an apparatus for the treatment of tobacco waste in combination a partitioned overflow tank, a container, communicating with the bottom part of said overflow tank, a trough-shaped container communicating with said first mentioned container, an adjustable sheet forming roller eccentrically mounted in said trough, an overflow tank adjacent said trough, and liquid moving means operatively connected to said overflow tanks, rotatable liquid baffling and propelling means in parallel relation to said roller and in the lower part of said container adjacent the trough, said baffling means being of laterally decreasing widths, an adjustable sheet forming, compressing

and desiccating roller, sheet supporting and propelling rollers associated therewith, and sheet coating and sheet drying rollers.

6. A machine of the character set forth, 5 including a tank having a rear, a front and an intermediate compartment, the rear and intermediate compartments communicating at the upper side of the tank and the front and intermediate compartments communicating 10 at the lower side of the tank, a pulp vat located in the front compartment and having its front, bottom, and rear walls spaced from the corresponding walls of said compartment, and a making cylinder journaled in the vat.

7. A machine of the character set forth, including a tank having a rear, a front and an intermediate compartment, the rear and intermediate compartments communicating 20 at the upper side of the tank and the front and intermediate compartments communicating 25 at the lower side of the tank, a pulp vat located in the front compartment and having its front, bottom, and rear walls spaced from the corresponding walls of said compartment, an agitator located in the front compartment adjacent the rear lower end of the vat, and a making cylinder journaled in the vat.

8. A machine of the character set forth, including a tank, a pulp vat located within the tank and communicating therewith at its upper front end only, a making cylinder journaled in the vat, a trough located at 35 the upper front end of the vat, and means adapted to convey the pulp accumulating in the trough to the tank in rear of the vat.

9. A machine of the character set forth, including a tank, a pulp vat located within 40 the tank, a making cylinder journaled in the vat, a trough located in the tank in front of the vat, and means adapted to convey the pulp accumulating in the trough to the tank in rear of the vat.

10. A machine of the character set forth, 45 including a tank, a pulp vat located within the tank and communicating therewith at its upper front end only, the front, bottom and rear walls of the vat being spaced from 50 the corresponding walls of the tank, a making cylinder journaled in the vat, an agitator journaled in the tank adjacent the lower rear end of the vat, and baffles located in the tank between the rear wall thereof and said 55 agitator.

11. A machine of the character set forth,

including heating rolls, an apron passing about said heating rolls, means for forming and delivering a web to said apron, supporting means located above said heating 60 rolls and over which the web is adapted to travel, and means adapted to apply a coating to said web during its passage over said supporting means, said coating means including a roller arranged on each side of 65 the web, a liquid containing tank, means supplying liquid from the tank to one of said coating rollers, and a tank in which the other coating roller rotates.

12. A machine of the character set forth, 70 including heating rolls, an apron passing about said heating rolls, means for forming and delivering a web to said apron, supporting means located above said heating rolls and over which the web is adapted to travel 75 out of engagement with said apron, and means adapted to apply a coating to said web during its passage over said supporting means, said coating means including upper and lower rollers, a pan located beneath 80 the lower roller, a trough located above the upper roller, means conveying liquid from the trough to the upper roller, and means contacting with said rollers to prevent an excess accumulation of coating liquid 85 thereon.

13. A machine of the character set forth, including heating rolls, an apron passing about said heating rolls, means for forming and delivering a web to said apron, a reel 90 adapted to receive the web and located forwardly of said heating rolls, and means adapted to rotatably support the reel in contact with said apron, the movement of the apron imparting rotation to the reel. 95

14. A machine of the character set forth including a first felt and supporting means therefor, a making cylinder engaged by said felt, a second felt having a point of contact with said first felt, supporting means 100 for said second felt, press rolls located adjacent the point of contact between said felts and between which said felts pass, and a suction box adapted to transfer the web from the first felt to the second felt at said 105 point of contact.

In testimony whereof I affix my signature in presence of two witnesses.

WILLARD J. GOODFELLOW.
